UNITED STATES PATENT OFFICE.

WILLIAM BRUSH, OF WEEHAWKEN, NEW JERSEY.

DENTAL CAN.

No. 811,370.

Specification of Letters Patent.

Patented Jan. 30, 1906.

Application filed June 6, 1905. Serial No. 263,914.

To all whom it may concern:

Be it known that I, WILLIAM BRUSH, a citizen of the United States, residing at Weehawken, Hudson county, State of New Jersey, have invented new and useful Improvements in Dental Cans, of which the following is a specification.

This invention relates to a dental can adapted to contain tooth-powder and also to contain a dental thread and deliver the same in lengths suitable for cleaning the teeth.

In the accompanying drawings, Figure 1 is a side view of my improved dental can; Fig. 2, a side view of the lower part thereof with the cap removed; Fig. 3, a vertical section of the lower part of the can with the cap in place, and Fig. 4 a horizontal section on line 4 4, Fig. 1.

The letter *a* represents a can for holding tooth-powder which is discharged by nozzle *a'*. The bottom *a²* of the can is countersunk, so that a circular flange *a³* depends from the bottom. This flange is notched, as at *a⁴*, and is embraced by a circular cap *b*, which constitutes a lower compartment. The rim of cap *b* is provided with a perforation *b'* and with a tongue *b²*, which is stamped out of the body of the cap and is placed at a distance

from perforation *b'*. The edge of tongue *b²* is sharpened to constitute a cutter. 30

A reel *c*, upon which is wound a waxed silk thread *d*, is contained within cap *b*, the end of the thread projecting outward through the alined notch *a⁴* and perforation *b'*. When the thread is to be used, the proper length is 35 drawn out and the thread is laid over tongue *b²* and cut off by pressure. It will be observed that after the thread has been so severed a length of thread equal to the distance between perforation *b'* and tongue *b²* still remains exposed ready to be grasped during the next operation.

What I claim is—

A dental can provided with a countersunk bottom, a depending flange having a notch, a 45 cap removably embracing the flange and having a perforation adapted to be alined with the notch, and a tongue, substantially as specified.

Signed by me at New York city, (Manhattan,) New York, this 5th day of June, 1905.

WILLIAM BRUSH.
